UNITED STATES PATENT OFFICE

144,013

DESIGN FOR A MOCK MACHINE GUN AND WING ATTACHMENT FOR BICYCLES

William J. Ward, Kansas City, Mo.

Application July 27, 1945, Serial No. 121,018

Term of patent 14 years

(Cl. D34—15)

To all whom it may concern:

Be it known that I, William J. Ward, a citizen of the United States, residing at Kansas City, county of Jackson, State of Missouri, have invented a new, original, and ornamental design for a Mock Machine Gun and Wing Attachment for Bicycles, of which the following is a specification, reference being had to the accompanying drawing, forming part thereof, in which

Fig. 1 is a top plan view of a mock machine gun and wing attachment for bicycles embodying my new design,

Fig. 2 is a rear elevational view of the mock machine gun and wing attachment for bicycles shown in Fig. 1.

Fig. 3 is a side elevational view thereof.

I claim:

The ornamental design for a mock machine gun and wing attachment for bicycles, substantially as shown.

WILLIAM J. WARD.
